AIR CONDITIONING SYSTEM

Frank L. Murphy, Chicago, Ill., assignor to Pullman-Standard Car Manufacturing Company, Chicago, Ill., a corporation of Delaware

Application January 12, 1939, Serial No. 250,529

5 Claims. (Cl. 257—3)

The present invention relates to an air conditioning system for a rail car and one of its principal objects is to provide a system which produces an even temperature throughout the passenger space. Other objects and advantages will become apparent as the disclosure proceeds and the description is read in conjunction with the accompanying drawings, in which

Fig. 1 is a diagrammatic view of the car interior showing the relative positions of the individual rooms with the air distribution system overhead;

Fig. 2 is a diagrammatic plan view showing the relative positions of the central ducts and the rooms;

Fig. 3 is an enlarged fragmentary transverse sectional view taken through the car body, showing on one side of the aisle in true section the fresh air discharge port into the room and on the other side of the aisle the exhaust air outlet from a room, with a portion of the outlet broken away.

Fig. 4 is a wiring diagram showing the complete controls for the heating and cooling systems.

For the purpose of disclosure only, a particular embodiment of the present invention has been selected, but obviously many changes may be made without departing from the scope of the invention.

The requirement for air conditioning in a railway car is not uniform throughout the entire car body interior. As an example of this situation, let it be assumed that a car is operating in cold weather at a time of year when there is considerable warmth in the sun's rays. With the sun shining on one side of the car only, the effect of the sun's rays will be felt only on that side of the car, so that the demand for car heating will be less on the sunny side of the car than on the shady side. If the air conditioning system for the car is controlled by a single thermostat situated, for example, on the sunny side, the conditioning system will operate in response to temperature conditions on the sunny or warm side of the car, so that, unless the thermostat is set to a higher degree than would be required for maximum comfort on the sunny side, the occupants in space situated on the shady side of the car will suffer. Likewise, if the thermostat is situated on the shady side, the passengers occupying the space on the sunny side will be uncomfortably warm.

The same situation will be present when the car is operating in warm weather and the cooling system is functioning; one side of the car is going to be either too warm or too cool. There are factors other than the sun to be considered, as, for example, the wind, but the problem is the same whatever may be the cause.

The present invention is intended to provide a means for uniformly conditioning the air

throughout the car interior, and this is accomplished by employing two or more complete air conditioning and circulating systems, each controlled separately by separate thermostatic controls.

GENERAL ORGANIZATION

The invention is shown applied to a railway car generally indicated at 10, having an under-frame 11 (see Fig. 3), a pair of side frames 12 and 13, and a roof 14. As shown, a vestibule 15 is provided at one end of the car having the usual vestibule doors 16, and at the other end of the car is positioned a dummy end generally indicated at 15'.

For the purpose of disclosure, the car body interior is shown provided with a plurality of roomette sections generally indicated at 17, positioned on both sides of an aisle 18 which extends throughout the length of the car and is positioned substantially along the car center line.

Each roomette section is provided with suitable accommodations, some of which are shown, and include a hopper 19, an upholstered seat 20 positioned over the hopper, and toilet facilities, including a wash basin 21, a medicine cabinet 22, a wardrobe 23, and other furnishings, including the bed (not shown). A baggage rack 24 may be provided for each room, and a door 25 permits access into the room from the aisle 18. Windows 26 are spaced along the car sides so as to provide at least one window for each roomette section.

AIR CONDITIONING SYSTEM

35 The air conditioning system forming the subject matter of the present invention includes both cooling and heating, the cooling being furnished by means of mechanical refrigeration or other suitable means and the heating being supplied by steam coils, electric heaters, or the like.

As shown in Fig. 4, the cooling is furnished by mechanical refrigeration, which includes the usual compressor 1, condenser 3, and a receiver 9, mounted underneath the car in the usual manner, a pair of expansion valves (not shown), evaporators 42 and 43, positioned in the conditioned air duct, and suitable piping generally indicated at 6. The compressor 1 may be driven from the car axle, as generally indicated at 53, and for standby service from an alternating current motor 54. The heating is supplied by steam heating coils drawing steam from the usual train line.

Air distribution

Extending throughout substantially the entire length of the car are a pair of conditioned air ducts 27 and 28, mounted side by side, and a pair of exhaust air ducts 29 and 30, positioned above the conditioned air ducts, as shown in Fig. 3.

CONTROL SYSTEM

Circuit in general

Separate blower fans 31 and 31' circulate air through the conditioned air ducts 27 and 28 respectively, and these fans draw their air from a plenum chamber 32 which is supplied with recirculated air drawn from the car interior through a recirculated air intake 33 and fresh air which is drawn in from the car vestibule through a fresh air intake 34. A damper arrangement, generally indicated at 35, regulates the proportion of recirculated and fresh air brought into the system. The conditioned air duct 27 discharges into the roomette sections positioned along car side 12 while the air duct 28 discharges into sections positioned along car side 13. This conditioned air enters each roomette section 17 through a grill 36, and the greater portion of this air is drawn through an opening 37, positioned in the door of each roomette section adjacent to the floor, and is then passed through the aisle 18 back into the plenum chamber 32 through recirculated air intake 33.

A small portion of air is exhausted from each of the roomette sections 17 through an exhaust outlet 38 and duct 39 into the exhaust air ducts 29 or 30, the ducts being arranged to draw from opposite sides of the car. An exhaust fan 40 is positioned at the end of the exhaust air ducts 29 and 30 and discharges from the car body through duct 41.

The air circulation throughout the car body is as follows: The blower fans 31 and 31' draw air from the plenum chamber 32 and pass this air through the ducts 27 and 28 and into the roomette sections 17 positioned on opposite sides of the car. The greater portion of this air is then passed through the openings 37 positioned in the doors 25 and is then returned through the aisle 18 to the plenum chamber 32 through the inlet 33. Occupants of roomette sections are permitted to smoke while in their sections, and consequently there is an accumulation of a large amount of smoke which cannot be properly taken care of by the air conditioning system if drawn back into the plenum chamber 32 and recirculated. Consequently, a portion of this smoke, together with other gases and a small percentage of vitiated air, is exhausted from each room through the outlet 38 into the ducts 29 and 30, and hence it is discharged from the car by means of exhaust fan 40.

The temperature of the air passing through the conditioned air ducts 27 and 28 is regulated by cooling coils 42 and 43, one being positioned in each of the ducts 27 and 28, and heating coils 44 and 45 positioned in the conditioned air ducts 27 and 28 respectively.

The cooling coils 42 and 43 in the present case are evaporators being supplied with refrigeration from a compressor 7 (Fig. 4) which may be mounted underneath the car in the usual manner.

The operation of the over-head heating coils is controlled by separate thermostats 46 and 47 positioned in the conditioned air ducts 27 and 28 respectively, while the operation of the cooling coils 42 and 43 is controlled by thermostats 48 and 49 positioned in the exhaust air ducts 29 and 30 respectively.

Floor heating coils 50 are positioned in each section and their operation is controlled by thermostats 51 and 52 positioned in the exhaust air ducts 29 and 30 respectively and controlling the operation of the coils on the opposite sides of the car independently of each other.

5 The control circuit includes generally a source of current, which is shown as a battery but may be a car generator or any other suitable source, a blower fan switch 56 operating a circuit to the blower fan motor 57, and a seasonal selector switch generally indicated at 58 generally positioned on the electric control panels at one end of the car. This selector switch places different parts of the control system in operation and is manipulated by a member of the train crew.

15 In addition to these elements, the control circuit also includes an overhead heat relay 59, which responds to the action of the overhead heat thermostat 46 to control the operation of heating coil 44, and a second overhead heat relay 60 which controls the operation of the heating coil 45 in response to thermostat 47. The floor heating coils, indicated at 50 in Fig. 3, are controlled by relays 61 and 62 which function in response to the thermostats 51 and 52 respectively. Floor heat relay 61 controls the operation of the floor coils situated adjacent to car side 12, and relay 62 controls the operation of the heating coils positioned adjacent to car side 13.

20 The operation of the cooling system is controlled by a pair of cooling pilot relays 62 and 63 which control the operation of evaporators 42 and 43 respectively through solenoid valves 64 and 65 respectively.

25 For standby service, the alternating current motor 54 drives the compressor 7 to produce refrigeration and current for running this motor is obtained from an outside source which is plugged in at the receptacle indicated at 66. An A. C. motor contactor relay 67 controls the operation of the A. C. circuit.

30 In addition to these various controls, the present system also includes a heat protection relay 68 which functions to prevent freezing up of the water pipes, etc., in a car, in the event that the car is standing in the yards, irrespective of the setting of the seasonal selector switch 58 and at a time when the blower fan switch 56 is turned off. This heat protection relay operates in response to a heat protection thermostat 69 and controls the floor heat.

Operation of the control system

35 To place the system in operation, the blower fan switch 56 is first closed to the dotted line position indicated at 70, thereby placing the blower fans 31 and 31' in operation. The speed of the fans may be varied by selectively changing the amount of resistance in the fan motor field 71 by means of a rheostat 72 and by changing the resistance in the armature circuit of the blower fan motor 57 by means of a second rheostat 73. When the blower fan switch 56 is closed, the fan is placed in operation and air is circulating through the ducts 27 and 28. The seasonal selector switch 58 is then turned to the position for cooling or heating, depending upon the season of the year in which the car is operating or upon outside temperature conditions.

Car operating in cold weather

40 As shown in Fig. 4, certain of the contacts in the seasonal selector switch lead to the heat control circuits, while other contacts lead to the control circuits for the cooling system.

45 75 Assume for the present that the car is operat-

ing in cold weather so that the seasonal selector switch is positioned for cold weather operation, as, for example, in the position indicated in dotted lines at 14. When the blower fan switch 56 is closed to the dotted line position, the current will flow from the positive terminal +R through the fan switch, conductors 75, 76, and 77, contact plate 78, seasonal selector switch blade 74, contact plate 79, conductors 80 and 81, then through the overhead heat relays 60 and 59, and then back to the negative terminal -R through conductor 82. Thus the overhead heat relays 59 and 60 are being energized so as to place the relay switches 59' and 60' in the dotted line position so as to complete the circuit to the overhead heat magnetic valves to maintain them in the "on" position.

The current also flows from the positive terminal +B through conductors 83, 84, and 85, contact plate 86, through seasonal selector switch blade 74, to contact plate 87, conductors 88 and 89, then through the floor heat relays 62 and 61, and then back to the negative terminal -B through conductors 90 and 91. Thus the floor heat relays 61 and 62 are being energized to hold the switches 61' and 62' in the dotted line position so as to maintain the floor heat magnetic valves 84 and 85 in the "on" position.

If any one or more of the thermostats 46, 47, 51, and 52 demand heating, the mercury in the thermostat or thermostats will be in a position to complete the circuit through the thermostat, thereby causing the current to by-pass the corresponding heat relay so as to deenergize the relay and move the corresponding relay switch to its solid line position, thereby turning off the corresponding heat magnetic valve.

Provision is made for varying the temperature of operation of the overhead heat thermostats 46 and 47 and the floor heating thermostats 51 and 52 by providing suitable heater elements 97 and 98 around the overhead and floor heating thermostats respectively. To add varying amounts of heat to the mercury in the thermostats, a bank of resistors, generally indicated at 99, made up of resistor elements of varying degrees of ohms for each resistor element, is placed in the heater circuit for each of the overhead heat thermostats 46 and 47 so as to permit varying the current flow through the heater elements. The position of the seasonal selector switch 58 will determine the amount of resistance in the thermostat heating element circuits. A second position of the seasonal selector switch is indicated at 92.

Similarly, the current flowing through the heating elements for the floor heat thermostats 51 and 52 may be varied.

A circuit breaker 101 is placed in the control circuit which functions when an over-load, due to a short or the like, is placed on the control circuit, and when this circuit breaker is opened a pilot light 102 is placed in the circuit to indicate trouble.

When the blower fan switch 56 is turned to the "off" position, indicated in solid lines in Fig. 4, the blower fan ceases operating and the entire control circuit becomes dead except for the heat protection relay circuit which operates in response to the heat protection thermostat 69 to prevent freezing of the water pipes, etc., in the car. When this thermostat calls for heating, the heat protection relay 68 becomes energized, closing the circuit to the floor heating system, thereby supplying heat to the floor heating coils. 75

In each of the floor heat control circuits is a ballast resistor 93, whose function is to prevent flow of current passing from the seasonal selector switch through the floor heat thermostat heater elements 98. When the circuit is completed through the dotted line position of each of the floor heat relay switches 61' and 62', there is a flow of current through the ballast resistor 93, which supplements the normal flow of current through the floor heat thermostat heater elements 51 and 52, thereby greatly increasing the speed of operation of the thermostats to make them much more sensitive in their response to the temperature conditions of the car interior.

There is a corresponding ballast resistor 110 for each of the overhead heat thermostats, and its function is to increase the sensitivity of the overhead heat thermostats.

Car operating in warm weather

For warm weather operation of the air conditioning system, the seasonal selector switch 58 is placed in the position shown in dotted lines at 103, in which position the control circuit for the cooling system becomes energized and the heating control circuits become dead except for the heat protection relay circuit.

With the seasonal selector switch in the position 103 and cooling thermostats 48 and 49 both calling for cooling, the cooling pilot relays 62 and 63 are de-energized, closing the circuits across the pilot relay switches 62' and 63' respectively, opening the solenoid valves 64 and 65 to complete the refrigeration cycle from the compressor 7.

Refrigeration is now being produced and the blower fan 31 is delivering cool air into both sides of the car. When the car interior is cooled sufficiently on one or both sides of the aisle, either or both of the cooling thermostats 48 and 49 cause the corresponding cooling pilot relays 62 and 63 to become de-energized, thereby opening either or both of the switches 62' and 63'. This closes one or both of the solenoid valves 64 and 65.

Assume for present purposes that the roomette sections adjacent to car side 12 are cooled down the proper amount before the sections adjacent to car side 13 so that cooling thermostat 48 ceases calling for cooling, while thermostat 49 continues to demand cooling. Under these conditions, blower fan 31 will circulate through the conditioned air duct 27 air at a temperature corresponding to temperature conditions in the plenum chamber, while the blower fan 31' will pass air over the evaporator 43, which is being cooled so as to pass air through conditioned air duct 28 at a temperature considerably below plenum chamber temperature conditions. Thus we have the situation where we are cooling the air along one side of the car only, thereby producing a uniform temperature throughout the car interior.

In the present disclosure, cooling thermostats 48 and 49 are made up of three thermostatic units each, each of which units is designed to function at a different critical temperature. Seasonal selector switch 58 may be adjusted to select any one of the three thermostatic units in each of the cooling thermostats 48 and 49, thereby affording a choice as to what temperature the cooling thermostats 48 and 49 will function to operate the cooling pilot relay.

Since the compressor 7 is driven from the car axle 53 when the car is in motion, a speed con-

trol, generally indicated at 104, is provided to limit the speed of operation of the compressor during high speed operation of the car. A speed control relay indicated at 105 controls the operation of this speed control, but, since it forms no part of the present invention, a detailed description is believed unnecessary.

The relays 62 and 63 are connected in parallel so that the speed control relay 105 is de-energized only when both of the cooling pilot relays become de-energized. Thus it is seen that, if either or both of the cooling pilot relays are energized so as to be calling for car cooling, the compressor 7 is operating.

It is thus seen that the air conditioning system forming the subject matter of the present invention provides uniform temperature conditions throughout all the sections in the car body by providing means for cooling one portion of the car when that portion requires cooling at a time when another portion of the car does not require cooling.

The electric current source for energizing the control circuit as shown is a battery, but, obviously, a generator may be employed if desired. The battery terminals are indicated by the letters B, R, and L, the B and R terminals being at all times in a position to supply current to the circuit when the proper switches are closed, but the L circuit may be closed only when the master light switch, positioned on the electric control panels, is in a closed position. Thus when the car is in the yards and the master light switch is turned off, the L terminal of the battery is dead.

Fuses 106 are placed in the various circuits for protection purposes.

A manual switch 107 is provided in each of the heating relay circuits, and its function is to permit manual control of the magnetic heat valves in the event the valves fail to operate automatically.

What I claim is:

1. In a vehicle having a plurality of zones with different air conditioning load demands, a conditioned air duct for each zone, an exhaust air duct for each zone, heating means in each conditioned air duct, thermostatic control means in each conditioned air duct for controlling the operation of its corresponding heating means, auxiliary heating means distributed throughout each zone, thermostatic control means in each exhaust air duct responsive to the mean temperature in its corresponding zone for controlling the operation of the auxiliary heating means, air circulating means for passing air through the conditioned air ducts, and means for discharging the exhaust air from the exhaust air ducts.

2. In a vehicle, an air conditioning system including a conditioned air duct discharging on one side of the vehicle, a second conditioned air duct discharging on the other side of the vehicle, a pair of exhaust air ducts adapted to withdraw air from opposite sides of the vehicle and discharge it from the vehicle body, heating means in each conditioned air duct, thermostatic control means in each conditioned air duct for controlling the operation of its corresponding heating means, auxiliary heating means in each side of the vehicle, thermostatic control means in each exhaust air duct for controlling the auxiliary heating means on the corresponding side of the vehicle, and means for passing air through the conditioned and exhaust air ducts.

side of the vehicle, and means for passing air through the conditioned and exhaust air ducts.

3. In a railway car having an aisle extending lengthwise along the center of the car, two zones each comprising a plurality of rooms on opposite sides of the aisle, air conditioning means comprising a separate air supply duct extending along the aisle for each zone and having an outlet opening into each room thereof, separate heat exchange means in each supply duct adjacent to the inlet to said duct and anterior to all the rooms of the zone supplied by said duct, blower means for passing air through the ducts, said rooms and air supply ducts having openings to the aisle for recirculation of most of the air supplied to said rooms, a separate air exhaust duct extending along the aisle for each zone and having an outlet opening from each room thereof for withdrawing a relatively small portion of the air therein, means discharging the last named portions to the exterior of the vehicle, and separate thermostatic means responsive to air in each exhaust duct posterior to the outlets from all of the rooms served by said duct controlling the heat exchange means for all of said last named rooms, whereby each room of the vehicle is normally supplied with an unvarying quantity of air and the temperature of the air supplied to each zone is determined by the average temperature exhausted from the rooms thereof.

4. In a railway car having an aisle extending lengthwise thereto, a plurality of zones in the car, air conditioning means comprising a separate air supply duct for each zone extending lengthwise to the car and having an outlet opening into each zone, separate heat exchange means in each supply duct adjacent to the inlet to said duct and anterior to the zones supplied by said duct, blower means for passing air through the ducts, said zones and ducts having openings to the aisle for recirculation of most of the air supplied to said zones, a separate air exhaust duct for each zone having an outlet from its corresponding zone for withdrawing a relatively small portion of the air therein, means discharging the last named portions to the exterior of the vehicle and separate thermostatic means responsive to air in each exhaust duct posterior to the outlet of the zone served by said duct controlling the heat exchange means for said zone.

5. In a vehicle, a plurality of rooms on opposite sides of a central aisle of said vehicle, an air conditioning system including a conditioned air duct discharging on one side of the vehicle into the rooms on the said side of the vehicle, a second conditioned air duct discharging into the rooms on the other side of the vehicle, a pair of exhaust ducts adapted to withdraw air from the rooms on opposite sides of the vehicle and discharge it from the vehicle body, heating means in each conditioned air duct, thermostatic control means in each conditioned air duct for controlling the operation of the corresponding heating means, auxiliary means in each side of the vehicle in the rooms thereof, thermostatic control means in each exhaust air duct for controlling the auxiliary heating means on the corresponding side of the vehicle, and means for passing air through the conditioned and exhaust air ducts.

FRANK L. MURPHY.
